(57) **CLAIM**

We claim the ornamental design for a battery charger and synchronizing device, as shown.

DESCRIPTION

FIG. 1 is a perspective view of a design for the battery charger and synchronizing device;
FIG. 2 is a top plan view thereof;
FIG. 3 is a bottom plan view thereof;
FIG. 4 is a front elevational view thereof;
FIG. 5 is a rear elevational view thereof;
FIG. 6 is a left side elevational view thereof; and,
FIG. 7 is a right side elevational view thereof.
